A CORPORATION OF MINNESOTA

DESIGN FOR A TOASTER

Application filed March 28, 1930. Serial No. 35,060. Term of patent 7 years.

To all whom it may concern:

Be it known that we, WILLIAM H. McLELLAND and GEORGE O. KNUTSON, citizens of the United States, residing at Minneapolis, in the county of Hennepin and State of Minnesota, have invented a new, original, and ornamental Design for a Toaster, of which the following is a specification, reference being had to the accompanying drawing, forming part thereof, wherein—

Fig. 1 is a perspective view of the toaster showing our new design.

Fig. 2 is an elevation showing the opposite side; and

Fig. 3 is a front elevation of the same.

What we claim is:

The ornamental design for a toaster substantially as shown.

WILLIAM H. McLELLAND.
GEORGE O. KNUTSON.
